ADVERTISING TOWER

Filed Dec. 20, 1928

INVENTOR:
ROBERT N. BAKER.
BY Bakewell & Church.
ATTORNEY.

UNITED STATES PATENT OFFICE

ROBERT N. BAKER, OF FORT WORTH, TEXAS

ADVERTISING TOWER

Application filed December 20, 1928. Serial No. 327,283.

This invention relates to advertising devices of the kind that are used principally to attract the attention of persons traveling on highways, railroads and railways in rural 5 districts or sparsely populated localities.

One object of my invention is to provide a novel advertising device, which is of such design that it will attract the attention of a person traveling towards the device long before said person is close enough to the device to read the advertisement on same, thereby causing the observer's attention to be attracted and held for a sufficiently long period to produce a lasting impression of the advertisement carried by the device.

Another object is to produce an illuminated advertisement carrying device which is of such construction or design that when observed at night from a distance, it creates 20 or produces the impression of a brightly illuminated object suspended in mid air above an illuminated shaft of less brilliancy.

Another object is to provide an advertising device that is ornamental and efficient as 25 a daylight advertising medium and also highly efficient and novel as a night advertising device.

Another object is to provide a device of the character previously described, that can be 30 illuminated at a sufficiently low cost to make its use for advertising purposes in rural districts commercially feasible.

And still another object is to provide an advertising tower, which, in addition to having 35 the desirable characteristics or features above described, is practically indestructible and capable of being erected quickly and at a comparatively low cost.

40 Figure 1 of the drawings is an elevational view of an advertising tower constructed in accordance with my invention.

Figure 2 is a top plan view of said tower; and

45 Figure 3 is a fragmentary vertical sectional

view, illustrating the portion of the tower in proximity to the base of the dome.

Referring to the drawings which illustrate the preferred form of my invention, A designates a tower that is adapted to be used principally to display an advertisement or a plurality of advertisements to the traveling public, and which, in most instances, will be located along a highway or in sufficiently close proximity to a railroad or navigable river to permit it to be readily seen by persons who are in transit. Said tower may be of any preferred height, usually, however, from 30 to 50 ft. high, and it may be of any preferred cross-sectional shape, either circular, oval, 50 rectangular, octagonal or hexagonal; it may be of uniform diameter from its base to its upper end, or it may be tapered inwardly slightly from its base towards its upper end. At the upper end of the tower is a cap piece 55 B, which may be of various shapes without departing from the spirit of my invention. Usually, the cap piece B will be constructed in the form of a dome, preferably a pointed dome, and the outer surface of said dome will 60 be painted or colored in such a way that the effect produced by the tower when it is illuminated, is that of a brilliantly illuminated object, preferably, a ball of fire, suspended in mid air above a vertically-disposed illuminated shaft of less brilliancy. Usually, the 65 portion of the tower below the dome that is used to carry the advertisement or advertisements, is painted white or some other suitable color that will produce a light background, and the dome is painted orange color, so that when beams of light are projected 70 onto the same, it will simulate a ball of fire.

At the base of the tower A are a plurality of flood lights 1 which are used to project 85 beams of light onto the advertisement carrying portion of the tower and illuminate said portion sufficiently to permit the advertising matter on same to be seen plainly from a considerable distance. Lights 2 of the flood 90

light type or any other suitable kind, are also arranged in such relationship with the dome B that beams or rays of light will be projected onto the dome in such a way as to illuminate the entire area of the dome. In order to produce an indirect lighting effect on the dome, the lights 2 are arranged inside of a member C that surrounds the base of the dome, the lights 2 being spaced outwardly some distance from the base of the dome and disposed upwardly so that the beams or rays of light from same will be projected upwardly and inwardly onto the surface of the dome. By changing the color of the lights 2, or changing the color of the outer surface of the dome B, various lighting effects can be obtained, but, as previously stated, I prefer to color the advertisement carrying portion and the dome of the tower and illuminate said portions in such a way that when observed at night from a distance, the dome B will appear to consist of a ball of fire suspended in mid air, thereby attracting and holding the attention of an observer long before the observer is able to read or clearly see the advertisement on the tower.

While the cross-sectional shape and longitudinal shape of the tower are immaterial, so far as my broad idea is concerned, I prefer to construct the tower in the form of a tube of circular shape in cross section, which tapers slightly or at such an angle that the beams or rays of light projected upwardly from the flood lights 1 will terminate at approximately the upper end of the advertisement carrying portion of the tower, thereby making it possible to illuminate the advertisement carrying portion throughout its entire height, with a few flood lights of sufficiently low candlepower to make it practicable to use the tower for advertising purpose in rural districts. In order to prevent the rays from the flood lights 1 from being projected onto the dome B, the tower is provided adjacent its upper end with an outwardly flared part D that effectively intercepts any upwardly-projecting rays from the flood lights 1 which otherwise might be projected onto the dome B, the member C, previously referred to, that conceals the lights 2 from view being of annular form or constructed in the form of a band that is carried by the outwardly flared part D of the tower. In order to produce a sharp line of demarcation between the dome B and the advertisement carrying portion of the tower when the tower is illuminated, thus accentuating the suspended fire ball effect produced by the dome, the outer surface of the annular band C is painted black. If desired, a plurality of holes 3 may be formed in the outwardly flared part D of the tower, so as to simulate windows located between the dome and the advertisement carrying portion of the tower, and vertically-disposed passage-

ways 3^a may be formed in the part D leading upwardly from the holes 3, as shown in Figure 3, so as to permit some of the light produced by the dome lights 2 to pass downwardly through the passageways 3^a, and thus produce the effect of lighted windows 3 beneath the band C.

An illuminated advertising tower of the construction above described produces a lasting impression of the advertising matter which it contains, due to the fact that a person approaching the tower and located a considerable distance away from the tower first sees what appears to be a ball of fire suspended in the air, thus creating an interest in the mind of an observer and holding the observer's attention until he comes in sufficiently close proximity to the tower to read or observe the advertisement which it contains. As the observer approaches the tower the effect produced is that of an illuminated shaft surmounted by a brilliantly illuminated object, which effect is not only very pleasing to the observer, but is also very useful to persons traveling in aeroplanes and similar machines, in that the light produced by the device serves as a beacon. My improved tower not only forms a novel and efficient illuminated device for night advertising, but it also forms a daylight advertising device which is both efficient and ornamental, due to its great height and the area of same that is available for advertising matter, and to the appearance of solidity, massiveness and symmetry which it presents to the traveling public. While the main function of the tower is that of an advertising medium, it is also capable of being used as a gasoline filling station, service station or restaurant, due to the fact that the base portion of the tower consists of a shell that can be used to form the side walls of a room or compartment of considerable size. When used for this purpose doors or windows may be mounted in the side wall of the base portion of the tower, as represented by the reference character 4 in Figure 1.

As previously stated, my improved tower can be constructed in various ways and from various kinds of materials. In order that it will be practically indestructible and in order that it may be erected quickly and at a sufficiently low cost to make its use for advertising purpose commercially feasible, I prefer to build the tower in the form of a monolithic structure, all of whose parts are integrally connected together. Thus, as shown in Figure 3, the tapered cylindrical shell that constitutes the advertisement carrying portion of the device, merges at its upper end into the dome B whose base is surrounded by the band C which merges into the outwardly flared part D, the structure being built by erecting a form or mold of the proper shape and then

filling it with concrete or other suitable material of a similar nature.

Having thus described my invention, what I claim as new and desire to secure by Letters Patent is:

5. 1. An advertising device, consisting of a tower provided with a cap piece, the portion of the tower below said cap piece being adapted to contain an advertisement, means for illuminating the cap piece and the advertisement carrying portion of the tower, and a band provided with a dark colored exterior for producing a line of demarcation between said cap piece and advertisement carrying portion.
10. 2. An advertising device, consisting of a tower provided with a dome, a portion of the tower below said dome being adapted to carry an advertisement, means for illuminating said advertisement carrying portion, lights arranged at the base of said dome and disposed so that the rays therefrom will be projected upwardly onto the surface of said dome, and a dark colored band located between the dome and advertisement carrying portion.
15. 3. An advertising device, consisting of a tower provided with a dome, a portion of the tower below said dome being adapted to carry an advertisement, means for illuminating said advertisement carrying portion, lights arranged at the base of said dome and disposed so that the rays therefrom will be projected upwardly onto the surface of said dome, and a means that tends to conceal the dome illuminating lights from view and produce a line of demarcation between the dome and the advertisement carrying portion of the tower.
20. 4. An advertising device, consisting of a tapered tower provided with a dome, the portion of the tower below said dome being adapted to carry an advertisement, flood lights at the base of the tower arranged so as to project rays of light onto the advertisement carrying portion of the tower throughout substantially the entire height of said portion, separate and distinct lights arranged adjacent the base of the dome and disposed so as to project rays of light upwardly over the surface of the dome, and means for producing a line of demarcation between said dome and advertisement carrying portion.
25. 5. An advertising device, consisting of a tapered tower provided with a dome, the portion of the tower below said dome being adapted to carry an advertisement, flood lights at the base of the tower arranged so as to project rays of light onto the advertisement carrying portion of the tower throughout substantially the entire height of said portion, separate and distinct lights arranged adjacent the base of the dome and disposed so as to project rays of light upwardly over the surface of the dome, an outwardly flared part intermediate the dome and the advertisement carrying portion of the tower, and a means for illuminating the
30. 6. An advertising device, consisting of a tapered tower provided adjacent its upper end with an outwardly flared part, a dome arranged above said outwardly flared part, lights arranged so as to illuminate the body portion of the tower below said outwardly flared part, lights arranged so as to illuminate the exterior of the dome, and a band arranged adjacent the base of the dome and surrounding the dome illuminating lights.
35. 7. An advertising device, consisting of a tower adapted to carry an advertisement and provided at its upper end with a cap piece, said advertisement carrying portion and cap piece being constructed in the form of an integral shell formed from concrete or the like, an outwardly flared part at the upper end of the advertisement carrying portion, a band carried by said outwardly flared part that surrounds the base of the cap piece, flood lights arranged at the base of the tower and disposed so as to project rays of light over the advertisement carrying portion of the tower throughout substantially the entire height of same, and lights arranged inside of said band and disposed so as to project rays of light onto the cap piece.
40. 8. An advertising device, consisting of a tapered tower provided at its upper end with a dome, the portion of the tower below said dome being adapted to carry an advertisement, an outwardly flared part on the tower located between the dome and the advertisement carrying portion, window openings in said outwardly flared part, and lights for illuminating the dome arranged so that rays from same will be visible through said window openings.
45. 9. An advertising device, consisting of a tower whose base portion is constructed so that it will serve as a room or compartment, a dome at the upper end of the tower whose exterior is colored to simulate fire, the portion of the tower below said dome having a light colored exterior and being adapted to carry an advertisement, and means for projecting beams of light onto said advertisement carrying portion and onto said dome, thereby producing the effect of a brilliantly lighted object suspended in mid air above an illuminated shaft of less brilliancy.
50. 10. An advertising device, consisting of a tall shaft-like structure provided with an advertisement carrying portion and with a cap piece, said advertising portion having a light colored exterior and said cap piece having an exterior that is colored so as to simulate fire, and separate and distinct means for

projecting rays of light onto said advertisement carrying portion and said cap piece.

11. An advertising device, consisting of a tall shaft-like structure provided with an advertisement carrying portion and with a cap piece, said advertising portion having a light colored exterior and said cap piece having an exterior that is colored so as to simulate fire, separate and distinct means for projecting rays of light onto said advertisement carrying portion and said cap piece, and a means located between said two separate portions that produces a dark zone between said portion when the device is illuminated.
